UNITED STATES PATENT OFFICE.

EMANUEL EINSTEIN, OF NEW YORK, N. Y.

DESIGN FOR NAP-SURFACE OF CLOTH.

SPECIFICATION forming part of Design No. 12,294, dated June 7, 1881.

Application filed March 14, 1881. Term of patent 3½ years.

To all whom it may concern:

Be it known that I, EMANUEL EINSTEIN, of New York city, have designed a new and original Design for the Nap-Surface of Cloths, of 5 which the following, in connection with the accompanying drawing, is a full, clear, and exact description.

This design is related to that class of designs which are intended to be cut into the 10 nap or pile of smooth-finished cloths in the act of shearing the same, such as shown in the patent of Felix Samson, dated February 15, 1881, No. 12,176; and while these designs might be produced on the cloth in other ways than 15 cutting, yet no other mode is contemplated nor is so desirable.

My present design is one of several of the aforesaid character filed on even date with this; and it consists in a special form and ar- 20 rangement of lines or grooves, producing a novel figured effect, as hereinafter set forth.

The figure in the annexed drawing gives a face view of a piece of cloth finished according to my design.

25 In this figure the field consists of the smooth-finished nap of the cloth forming a uniform

level surface, while the lines represent grooves cut into this nap.

This design, as may be now observed, consists in a series of parallel longitudinal bands, 30 *a a*, crossed by diagonal lines *b b*, with longitudinal stripes *c c*, lined with a wavy or serpentine line or lines *d d*, which alternate with the bands of diagonal lines, and thus give a diverse and pleasing effect to the combination. 35

A peculiar effect of these designs is due to the contrast of the smooth or level finished nap with the figures formed by the grooves cut into the same, and this effect could not be obtained so well by any other mode of pro- 40 ducing the design upon the cloth.

What I claim is—

The design for the nap-surface of cloth, consisting of parallel bands of diagonal lines alternating with longitudinal stripes of serpentine lines, substantially as herein described and 45 illustrated.

EMANUEL EINSTEIN.
